UNITED STATES PATENT OFFICE.

LOUIS LYONS, OF PROVIDENCE, RHODE ISLAND.

DESIGN FOR A RING, PIN, OR SIMILAR ARTICLE OF JEWELRY.

45,261.

Specification for Design.

Patented Feb. 17, 1914.

Application filed November 25, 1913. Serial No. 803,058. Term of patent 3½ years.

To all whom it may concern:

Be it known that I, LOUIS LYONS, a citizen of the United States, residing in the city and county of Providence, State of Rhode Island, have invented a new, original, and ornamental Design for a Ring, Pin, or Similar Article of Jewelry, of which the following is a specification, reference being had to the accompanying drawing, forming part thereof.

The figure is an edge view of a ring illustrating my new design.

I claim:

The ornamental design for a ring, pin, or similar article of jewelry, as shown.

LOUIS LYONS.

Witnesses:

HOWARD E. BARLOW,
E. I. OGDEN.
